UNITED STATES PATENT OFFICE.

GEORGE JUER, OF HOPEWELL, VIRGINIA, ASSIGNOR TO TUBIZE ARTIFICIAL SILK COMPANY OF AMERICA, OF WILMINGTON, DELAWARE, A CORPORATION OF DELAWARE.

ARTIFICIAL-SILK-SPINNING MACHINE.

Application filed December 30, 1920. Serial No. 434,000.

To all whom it may concern:

Be it known that I, GEORGE JUER, recently a subject of the former Austro-Hungarian Empire and now a resident of Hope-
well, in the county of Prince George, in the
State of Virginia, have invented certain
new and useful Improvements in Artificial-
Silk-Spinning Machines, of which the fol-
lowing is a true and exact description, ref-
erence being had to the accompanying draw-
ings, which form a part thereof.

My invention relates to mechanism for
forming filamental threads known as arti-
ficial silk filaments and has for its object
15 the formation of a yarn made up of a num-
ber of such filaments, which yarn will be as
nearly as possible uniform in weight and
thickness. Another object which I have in
view is in connection with the use of inter-
20 mittently acting pumps which alternately
force the collodion or other material through
the spinnerets to maintain a practical con-
tinuous flow of material through the spin-
nerets and I have also in view the combi-
25 nation with a spinneret header of two alter-
nately acting pumps, each having a holding
capacity for material to be formed into
filaments sufficient to produce a quantity of
yarn formed of filamental threads suffi-
30 cient to fill a bobbin or spool.

The nature of the invention which I have
made to carry out the above mentioned pri-
mary objects and to provide full mechanism
for doing so will be best understood in con-
35 nection with the drawings which illustrate
a machine embodying my invention and im-
provements in what I believe to be their
best and most practical form and in which

Figure 1 is a plan view of the machine
40 taken as on the section line 1—1 of Fig. 2.

Figure 2 is an elevation of the machine
taken on the line 2—2 of Fig. 1.

Figure 3 is an end view of the machine
45 taken as on the line 3—3 of Fig. 2.

Figure 4 is an end elevation on a larger
scale generally similar to Fig. 3 but showing
also the upper part of the threads and omit-
ting the clutch mechanism for driving the
main shaft, said shaft being shown in sec-
50 tion and the arms for supporting the first
worm wheel in position also shown partly
in section.

Figure 5 is a side elevation on a larger

scale of the mechanism shown at the right
hand side of Fig. 2, taken as on the section
line 5—5 of Fig. 6, and

Figure 6 is a plan view on a larger scale
of the mechanism shown at the right hand
side of Fig. 1.

Figure 7 is a cross sectional elevation
taken as on the line 7—7 of Fig. 2 with the
arms holding the worm wheel in place shown
in section.

Figure 8 is a plan view of the upper part
of the machine showing the arrangement
and disposition of the several supporting
headers.

Figure 9 is a sectional elevation of the
four-way valve by means of which the sup-
ply pipe and a header are alternately thrown
70 into communication with a pair of alter-
nately acting pumps by means of which a
direct communication is made from the sup-
ply pipe to the header during the shifting
of the valve.

Figure 10 is a perspective view of a detail
of the mechanism.

Figure 11 is a longitudinal sectional view
of one of the pump cylinders taken on the
line 11—11 of Fig. 12, and

Figure 12, an end view thereof and of
the gland used in connection therewith.

A, A, etc. indicate the vertical members of
the machine frame; A' A', transversely ex-
tending portions of the frame at the bottom
thereof; A², A², transversely extending por-
tions of the frame at the top thereof; A³, A³,
longitudinally extending beams supported,
as shown, on the frame portions A'. A⁴, A⁴,
are longitudinally extending rods supported
on the frame portions A². B, B', etc. are a
series of pump cylinders supported on the
beams A³ and wormed in pairs in alignment
with each other; each of these cylinders, as
shown, see Figs. 11 and 12, is provided with

95 a gland B² in its opposite end. C, C', indi-
cate plungers working in the opposite cylin-
ders B and B' and preferably, as shown,
formed in the ends of a continuous rod, the
central portion of which is screw threaded
as indicated at C². D is a nut screwing on
the threaded portion C² of the flange rod and
having a worm wheel D' formed on or se-
cured to its periphery. The nut and worm
wheel are held in fixed position by arms
100 D², D² supported on the frame of the ma-

chine. E is a shaft extending longitudinally of the machine and suitably supported on pedestals such as A⁵, such shaft having formed on or secured to it a series of worms E' in engagement with the worm wheels D' of the nuts D. E² is a sliding clutch member longitudinally movable on the shaft E but keyed to the shaft which has to revolve with it. E³ and E⁴ are co-acting clutch members free to revolve on the shaft E but held in fixed longitudinal position thereon. E⁵ and E⁶ are bevel gear wheels secured to the clutch members E³ and E⁴ and both engaged with the bevel gear F secured 10 to the main driving shaft F' which has also secured to it a gear wheel F² which engages a gear wheel G on a shaft G' on which shaft is keyed a clutch member G² free to slide longitudinally on the shaft so as to engage 15 with either the clutch member G³ or the clutch member G⁴ which are free to rotate on the shaft G' and each of which is provided with a bevel gear wheel indicated at G⁵, G⁶. These bevel gears are in engagement 20 with the horizontal bevel gear, indicated at H from which extends a finger or arm H'. The bevel gear H is supported on the lower end of a vertical shaft H² suitably supported on the machine and having an 25 elongated gear wheel H³ secured to its upper portion. This gear wheel in turn is in engagement with the rack I secured to a longitudinally extending bar I' which at 30 one end engages a lever arm I² secured to a shaft I³ to which shaft is also secured a forked lever I⁴ in engagement with the clutch member E². J is a forked lever in 35 engagement with the clutch member E² and actuated through a shaft J' and an arm J², best shown in Fig. 10, and which is preferably provided with spring arms J³ and J⁴ extending downward from its upper end. These spring arms, see Figs. 4 and 5, extend 40 into positions in which they lie in the path of the finger or arm H' extending out from the periphery of the bevel wheel H. K and K', best shown in Figs. 5 and 6, are fingers or arms extending out from a rod K², which rod is secured at one end to an arm K³ secured, as shown, to the plunger shaft of the plunger C, C', as by a ring K⁴ and held in 45 position by a guide rod K⁵. K⁶ indicates a guide secured, as shown, to the cylinder B' which supports the rod K² but permits it to slide thereon.

L is a supply conduit for the material to be converted into artificial silk filaments. This material is supplied to a conduit maintained under as nearly as possible constant pressure therein by means of pumps not shown, the pressure under which the material is maintained being as nearly as possible equal to that which is necessary to force it with the desired speed through the spinnerets attached to the various spinneret

headers connected with the conduit in the manner to be hereafter described. L', L', etc. are a series of pipes leading from the supply conduit, L, one being provided for each pair of connected pump cylinders. 70 Each pipe L leads to a four-way valve M from which leads a delivery pipe L². Also leading from the four-way valve M are pipes L³ and L⁴ connecting respectively with the opposite cylinders B and B' with each 75 pair of pump cylinders.

The construction of the four-way valve M is best shown in Fig. 9 which is provided with four parts m', m², m³ and m⁴ connected respectively with pipes L', L², L³ and L⁴ and to the cylindrical valve seat indicated at m⁵ in which works a cylindrical valve N having formed in it ports N' and N² supported by the partition N³ which partition is of such dimensions that, as is indicated 85 by dotted lines in Fig. 9, it will not close the ports m' and m² when turned into alignment with these ports and so that in moving the valve from the position shown in Fig. 9, for instance, to a position in which 90 the pipe connections are reversed a direct communication will be formed from the ports m' to the port m².

O, O, etc. are lever arms secured to the valves N at one end and connected at their 95 opposite end to the reciprocating rod or plate I'.

P indicates a filter which is connected with each of the pipes L² and from which a pipe P' or P² leads to a spinneret header Q. 100 and Q'. These spinneret headers are supported on the rods A⁴, A⁴, as shown, and are disposed in groups on opposite sides of the machine, each spinneret header having secured to and in connection therewith a group of spinnerets indicated at Q³, the filaments from the spinnerets of each header being guided and covered by fingers and grooves indicated at R, R' and R² so that 105 they form a yarn which is run on a bobbin or spool indicated at R³, Fig. 7.

The operation of the machine is as follows: Assuming the driving shaft F' to be in constant operation it is obvious that this motion is transmitted through the gears F² and G to the shaft G' and to the clutch member G² which slides on but rotates with this shaft. The bevel gear H secured to the shaft F' is also in constant rotation and transmits rotation in opposite directions to the bevel gears E⁵ and E⁶ and the clutch members E³ and E⁴ secured thereto and obviously the shaft E would be rotated in opposite directions depending on whether the clutch member E² is engaged with the clutch member E⁴ or the clutch member E³. The rotation of the shaft E imparts through the worms E' rotative movement to the worm wheels D' and the nuts D which, acting on the screw threaded intermediate portion 115 120 125 130

C^2 of the plunger rod imparts motion to the plunger C' and the cylinder B' . The capacity of the cylinders B and B' is preferably such that each will contain, when the plunger is retracted to its full extent, an amount of material sufficient when manufactured into yarn, to fill one bobbin or spool. This is quite important as it insures or may be made to insure that the filaments 10 into which the cylinder charge is manufactured and each charge to be manufactured into a yarn and wound upon a bobbin shall in all cases be made up of an equal weight of material, that is, that the yarn shall be of 15 uniform weight and it also provides or may be made to provide for the shifting of the yarn from a full bobbin to an empty bobbin during the interval between the reciprocating strokes of the pump, that is during the 20 period when an inequality in the weight of the yarn is most apt to occur.

The material to be converted into filaments is maintained in the conduit L under pressure as nearly as possible equal to the pressure 25 under which it is intended that the material shall be forced through the spinnerets and the valves N being, for instance, in the position shown in full lines in Fig. 9, the material flows through the conduit L 30 through the pipes L' into the port m' , thence through the valve port N' to the port m^2 into the pipe L^2 and from said pipe into the cylinders B in which the plungers C are moving downward at the same time the plunger C' 35 moving inward in the cylinders B' forces the material through the pipes L^4 into the ports m^4 and through the ports N^2 of the valve into the ports m^2 and thence through the pipes L^2 through the filters P into the 40 pipes P' and P^2 and into the headers Q and Q' from which the material issues through the spinnerets Q^2 , each header having connected to it a group of spinnerets equal in 45 number to the number of filaments which it is intended shall be formed into the cylinder and these filaments being gathered by the fingers R , groove R' and fingers R^2 into a yarn which is wound on one of the bobbins R^3 .

50 It will be obvious that owing to the pressure in the conduit L being substantially equal to the pressure maintained in the headers but little power will be required to move the plungers C , C' , the pressure transmitted 55 through the conduit to the receiving plunger C , for instance, being nearly sufficient to force the plunger C' into the cylinder B' with sufficient power to maintain the necessary pressure in the connected header.

60 At the end of each stroke of the connected pistons it is, of course, necessary to reverse the valves N and it is an important feature of my invention that I provide a valve which during its motion to reverse the flow of the 65 filament making material operating to pro-

vide a direct exit between the ports m' and m^2 . and I believe most efficient construction is that illustrated in Fig. 9 in which the partition N^3 between the ports N' and N^2 of the valve is made of such dimensions that in its intermediate position indicated in dotted lines it does not close the ports m' and m^2 but connects both of the valve ports N' and N^2 with the ports m' and m^2 so that during 70 the interval when the pump cylinders are reversed during the reversing movement of the plungers not feeding material to the headers the material from the conduit L will flow directly to the headers and maintain an approximately constant feed which will insure not only against a stoppage of flow but a nearly continuous flow so that even during this interval there will be little or no variation in the weight of the yarn. 75

To return now to the driving mechanism shown in the drawing, the clutch E^2 is in engagement with the clutch member E^4 so that the shaft E is being rotated by the said clutch member E^4 , the clutch member G^2 keyed to the shaft member G' is out of engagement with the clutch members G^3 and G^4 and consequently the bevel gears G^5 and G^6 and the bevel gear H are stationary. The lever J^2 lies in the position indicated in 80 Figs. 4 and 6 and, as indicated in Fig. 6, the plunger C' is about to begin its inward stroke in the cylinder B' as the plunger C' moves inward in its cylinder and the plunger C outward the collar K^4 travelling with the plunger rod moves the arm K^3 and the rod K^2 and toward the end of this movement on the finger K' comes in contact with the lever 85 J^2 moving it gradually until it passes over the center when the weight at the head of the lever causes it to fall and through the rock shaft J' and fork J moves the clutch member H^2 into engagement with the clutch member G^4 which seats the gear G^6 in rotation and causes the gear H to rotate also its attached shaft H^2 and the gear H^3 which, 90 acting on the rack I , performs two functions, first, through the lever I^2 , rack shaft I^3 and fork I^4 which first disengages the clutch member E^2 from the clutch member E^4 and at the end of this movement engages the clutch member E^2 with the clutch member E^3 , thus reversing the direction and rotation of the shaft E and through its geared connections reversing the direction and movement of the plungers in the cylinders. Second, the movement of the rod I' through the levers O reverse the valves N and through these valves, of course, reverse the connections of the cylinders B and B' with the supply conduit and the headers. 95

While these movements of the lever arm I^2 and of the levers O are taking place the rotation of the gear wheel H carries the finger H' through a circular position until

it comes in contact with one of the spring arms J^3 and J^2 on the lever J^4 and the yielding pressure thus applied turns the lever J^2 in a direction to move the clutch member H^2 5 out of engagement with the clutch member G^4 and when these clutch members have been disengaged the resilience of the spring through which the lever J^2 has been moved is such as to move it a short distance farther 10 so as to insure that the clutch members will be sufficiently apart to avoid the risk of a re-engagement. As soon as the clutch members are disengaged the rotation of the gear wheel H and its connected mechanism ceases 15 and these parts remain stationary until at the end of the reversed movement of the plungers the finger K comes in contact with the lever J^2 and moves it over the center so that it will engage the clutch member G^2 20 with the clutch member G^3 , causing the rotation of the gear wheel H in the opposite direction to that in which it revolved previously and through the mechanism described reversing the connection with the clutch member E^2 and reversing the operative position of the valves N . 25

While, as required by law, I have illustrated and described my invention in what I believe to be its best and most efficient embodiment I wish it to be clearly understood that my invention may be embodied in many modifications of the specific mechanism illustrated and that I do not wish to be understood as limiting my claims on any of the 30 specifically illustrated and described devices except where such devices are specifically called for in the claims.

Having now described my invention, what I claim as new and desire to secure by Letters Patent, is:

1. In a machine for forming artificial silk filaments, the combination with a supply conduit for the fluid to be formed into filaments of a series of spinneret headers each having a group of spinnerets equal in number to the number of filaments to be formed into a single yarn or thread and a series of pumps, one for each header, arranged to draw fluid from the supply conduit and force it into the connected headers. 45

2. In a machine for forming artificial silk filaments, the combination with a supply conduit for the fluid to be formed into filaments of a series of spinneret headers each having a group of spinnerets equal in number to the number of filaments to be formed into a single yarn or thread, a series of pumping mechanisms each made up of two reciprocally acting pumps the moving parts of which are connected to move in unison, pipes connecting each said pumping mechanism, with the supply conduit and with one of the series of headers and valve mechanisms whereby the pumps are alternately connected to the conduit during their

suction strokes and to their connected headers during their delivery strokes.

3. In a machine for forming artificial silk filaments, the combination with a supply conduit for the fluid to be formed into filaments of a series of spinneret headers each having a group of spinnerets equal in number to the number of filaments to be formed into a single yarn or thread, a series of pumping mechanisms each made up of two pump cylinders arranged in line and plungers working in said cylinders and connected together so as to make a working stroke in one cylinder and a suction stroke in the oppositely disposed cylinder, a conduit system 70 connecting each such pump mechanism with the supply conduit and with one spinneret header, and means operating in connection with said conduit system whereby the cylinders of each pump mechanism are alternately connected to the supply conduit and to said header. 75

4. In a machine for forming artificial silk filaments, the combination with a supply conduit for the fluid to be formed into filaments of a series of spinneret headers each having a group of spinnerets equal in number to the number of filaments to be formed into a single yarn or thread, a series of pumping mechanisms each made up of two pump cylinders arranged in line and plungers working in said cylinders and connected together so as to make a working stroke in one cylinder and a suction stroke in the oppositely disposed cylinder, means for actuating the pump plungers including reversing mechanism operating at the end of the plunger strokes, a valve casing connected to both cylinders of each pump mechanism and to the supply conduit and header, valve mechanism working in each casing to alternately connect each cylinder with the supply conduit and the header and means interconnecting the piston reversing and valve actuating mechanism so that the valve is shifted 100 as the pistons reverse. 105

5. In a machine for forming artificial silk filaments a supply conduit for the fluid to be formed into filaments, in combination with a spinneret header, two reciprocally acting pumps the moving parts of which are interconnected to move in unison, pipes connecting the pumps with the conduit and header and valve mechanism whereby the pumps are alternately connected to the conduit during their suction strokes, to the header during their delivery strokes and whereby the conduit and header are directly connected during the shifting of the valve mechanism. 115

6. In a machine for forming artificial silk filaments a supply conduit for the fluid to be formed into filaments, in combination with a header supplying a group of spinnerets, two pump cylinders, plungers work- 120

- ing in said cylinders connected to move together so as to make a suction stroke in one cylinder and an expulsion stroke in the other, a conduit system connecting the supply conduit with both cylinders and both cylinders with the spinneret header and means operating in connection with said conduit system whereby said cylinders are alternately connected to the supply conduit 5 and to the spinneret header and whereby direct connection is made between the supply conduit and header during the shifting of connections between the cylinders and the header.
- 10 7. In a machine for forming artificial silk filaments a supply conduit for the fluid to be formed into filaments, in combination with a header supplying a group of spinnerets, two pump cylinders arranged in line, connected plungers working in said cylinders, a valve casing, pipes connecting said valve casing to the supply conduit, the two cylinders and the header valve mechanism working in said casing whereby the cylinders 20 are alternately connected to the supply conduit and to the header and whereby direct connection is made between the header and supply conduit during the shifting of connections with the cylinders.
- 25 8. In a machine for forming artificial silk filaments a supply conduit for the fluid to be formed into filaments, in combination with a header supplying a group of spinnerets, two pump cylinders arranged in line, connected plungers working in said cylinders, a valve casing, pipes connecting said valve casing to the supply conduit, the two cylinders and the header and a four way valve working in said casing formed as described to make a direct connection between the supply conduit and the header during the movement of the valve to reverse the connections of the cylinders to the conduit 30 and header.
- 35 9. In a machine for forming artificial silk filaments a supply conduit for the fluid to be formed into filaments, in combination with a header supplying a group of spinnerets, two pump cylinders each having a holding capacity for sufficient collodion to be formed into filament yarns sufficient to fill one winding bobbin, plungers working in said cylinders connected to move together so as to make a suction stroke in one cylinder and an expulsion stroke in the other, a conduit system connecting the supply conduit with both cylinders and both cylinders with the spinneret header and means operating in connection with said conduit system whereby said cylinders are alternately connected to the supply conduit 40 and to the spinneret header and whereby direct connection is made between the supply conduit and header during the shifting of connections between the cylinders and the header.
- 45 10. In a machine for forming artificial silk filaments a supply conduit for the fluid to be formed into filaments, in combination with a header supplying a group of spinnerets, two pump cylinders arranged in line, a rod the ends of which form plungers working in the cylinders and the centre of which is screw threaded, a nut engaging the threaded rod held in fixed position between the cylinders and having a worm gear formed on it, a worm shaft engaging said gear, reversing driving mechanism for said shaft, a valve casing connected by pipes to the supply conduit the two cylinders and the header, a four way valve in said casing whereby the cylinders are alternately connected to the conduit and to the header, valve actuating mechanism and means actuated by the piston rod at the end of its reciprocating strokes for shifting the valve actuating mechanism and reversing the shaft driving mechanism.
- 50 11. In a machine for forming artificial silk filaments a supply conduit for the fluid to be formed into filaments, in combination with a header supplying a group of spinnerets, two pump cylinders arranged in line, a rod the ends of which form plungers working in the cylinders and the center of which is screw threaded, a nut engaging the threaded rod held in fixed position between the cylinders and having a worm gear formed on it, a worm shaft engaging said gear, reversing driving mechanism for said shaft, a valve casing connected by pipes to the supply conduit the two cylinders and the header, a four way valve in said casing whereby the cylinders are alternately connected to the conduit and to the header, and whereby the conduit and header are directly connected during the shifting of the valve, valve actuating mechanism, and means actuated by the piston rod at the end of its reciprocating strokes for shifting the valve actuating mechanism and reversing the shaft driving mechanism.
- 55 12. In a machine for forming artificial silk filaments a supply conduit for the fluid to be formed into filaments, in combination with a header supplying a group of spinnerets, two pump cylinders arranged in line, a rod the ends of which form plungers working in the cylinders and the center of which is screw threaded, a nut engaging the threaded rod held in fixed position between the cylinders and having a worm gear formed on it, a worm shaft engaging said gear, reversing driving mechanism for said shaft, a valve casing connected by pipes to the supply conduit the two cylinders and the header, a four way valve in said casing whereby the cylinders are alternately connected to the conduit and to the header, and whereby the conduit and header are directly connected during the shifting of the valve, valve actuating mechanism, and means actuated by the piston rod at the end of its reciprocating strokes for shifting the valve actuating mechanism and reversing the shaft driving mechanism.
- 60 13. In a machine for forming artificial silk filaments a supply conduit for the fluid to be formed into filaments, in combination with a header supplying a group of spinnerets, two pump cylinders arranged in line, a rod the ends of which form plungers working in the cylinders and the center of which is screw threaded, a nut engaging the threaded rod held in fixed position between the cylinders and having a worm gear formed on it, a worm shaft engaging said gear, reversing driving mechanism for said shaft, a valve casing connected by pipes to the supply conduit the two cylinders and the header, a four way valve in said casing whereby the cylinders are alternately connected to the conduit and to the header, and whereby the conduit and header are directly connected during the shifting of the valve, valve actuating mechanism, and means actuated by the piston rod at the end of its reciprocating strokes for shifting the valve actuating mechanism and reversing the shaft driving mechanism.
- 65 14. In a machine for forming artificial silk filaments a supply conduit for the fluid to be formed into filaments, in combination with a header supplying a group of spinnerets, two pump cylinders arranged in line, a rod the ends of which form plungers working in the cylinders and the center of which is screw threaded, a nut engaging the threaded rod held in fixed position between the cylinders and having a worm gear formed on it, a worm shaft engaging said gear, reversing driving mechanism for said shaft, a valve casing connected by pipes to the supply conduit the two cylinders and the header, a four way valve in said casing whereby the cylinders are alternately connected to the conduit and to the header, and whereby the conduit and header are directly connected during the shifting of the valve, valve actuating mechanism, and means actuated by the piston rod at the end of its reciprocating strokes for shifting the valve actuating mechanism and reversing the shaft driving mechanism.

13. In a machine for forming artificial silk filaments having a supply conduit a spinneret header, two reciprocally acting pumps, a four way valve casing, pipes connecting said casing with the conduit, the two pumps and the header and a valve whereby the pumps are alternately connected to the conduit and header, in combination with a source of power, a shaft for driving the pumps, reversing mechanism for connecting the shaft to the source of power, a rack connected to actuate the valve and the reversing mechanism of the pump shaft, a shaft gear connected to the source of power, a shaft and pinion connected to actuate the rack reversing mechanism for engaging said shaft with the gear actuated shaft including a reciprocating clutch, means moving with a moving part of the pump operating to engage said clutch with the reversing mechanism at the end of each pump stroke and means moving with the shaft geared to the rack whereby the clutch is disengaged from the reversing mechanism

when the rack has moved through a determined distance. 25

14. In a machine for forming artificial silk filaments having a supply conduit, a spinneret header, two reciprocally acting pumps, a four way valve casing, pipes connecting said casing with the conduit the two pumps and the header and a valve whereby the pumps are alternately connected to the conduit and header and whereby the conduit and header are directly connected while the valve is in intermediate position, in combination with a source of power, a shaft for drawing the pumps, reversing mechanism for connecting the shaft to the source of power, valve actuating mechanism, means operatively connecting the valve actuating mechanism to the shaft reversing mechanism and means operatively connected to a moving part of the pumps whereby the valve actuating mechanism is set in operation at the end of each pump stroke to reverse the valve. 30 35 40 45

GEORGE JUER.
